(57) **CLAIM**

What is claimed is the ornamental design for a console audio recording and playback system, as shown and described.

DESCRIPTION

FIG. 1 is a front perspective view showing the console audio recording and playback system of Applicants' invention. FIG. 2 is a front elevation of the console audio recording and playback system of Applicants' invention.

FIG. 3 is a right side elevation of the console audio recording and playback system of Applicants' invention.

FIG. 4 is a left side elevation of the console audio recording and playback system of Applicants' invention.

FIG. 5 is a rear elevation of the console audio recording and playback system of Applicants' invention.

FIG. 6 is a top view of the console audio recording and playback system of Applicants' invention; and,

FIG. 7 is a bottom view of the console audio recording and playback system of Applicants' invention.
